PATRICK J. MOORE, OF BUTTE, MONTANA.

PORTABLE ELECTRIC TOOL-DRIVING MACHINE.

Application filed May 29, 1928. Serial No. 281,553.

The present invention relates to improvements in portable electric tool driving machines, and has for an object to provide an improved machine of a compact, inexpensive form capable of operating shears, rotating sandstones, clothes brushes, screens for powders and seeds and a variety of other implements.

Another object of the invention is to so 10 construct the machine as to make provision for detaching one of the driven implements and substituting another.

A further object of the invention is to provide for the proper disposition of the electric cable to the motor whereby not to interfere with the portability of the machine, and its free movement in the application of the tool to the work.

With the foregoing and other objects in 20 view, the invention will be more fully described hereinafter, and will be more particularly pointed out in the claims appended hereto.

In the drawings, wherein like symbols 25 refer to like or corresponding parts throughout the several views,

Figure 1 is a side elevation of an improved machine constructed according to the present invention.

Figure 2 is a similar view taken from the 30 opposite side.

Figure 3 is a top plan view of the frame of the device.

Figure 4 is a top plan view of the machine with parts broken away.

Figure 5 is an enlarged cross sectional view taken on the line 5-5 in Figure 4.

Figure 6 is a fragmentary perspective view showing the joint between the frame 40 and removable tool parts.

Figure 7 is also a fragmentary perspective view showing the parts separated.

Figure 8 is a fragmentary perspective view showing the substitution on the machine of a 45 grinding or other roller.

Figure 9 is a similar view showing the application to the machine of a rotary brush, and

Figure 10 is also a fragmentary perspective view with the parts shown disassembled and illustrating the application of a sifting device.

Referring more particularly to the drawings 50 11 and 12 represent respectively the fixed and movable blades of a pair of shears. The lower fixed blade 11 is shown as extend-

ing in a forward upwardly inclined direction while the upper blade 12 is pivoted at the base of the upright 13 which supports, and may form a part of, the lower fixed blade 11. 60 The two blades are thus carried by the upright 13 which in turn is provided with the horizontal shank 14 adapted to detachably fit upon the portable machine.

Figures 6 and 7 show the preferred form 65 of joint. In these figures, the shank 14 is shown as having at its free end a lateral portion 15 removed; and projecting sideways from the face of the removed portion 15 is a lug 16, preferably square in cross 70 section for cooperating with a similarly formed opening 17 in the cooperating frame shank 18. The end 19 of this shank is beveled and fits against a beveled shoulder 20 on the tool shank 14.

This beveled arrangement assists in supporting the tool from the machine frame. A clamp, such as shown in Figure 6, is adapted to be fitted over the joint to hold the parts against separation. This clamp 80 is composed of the top portion 21, the sides or legs 22 and 23 and the dome or handle 24. The legs 22 and 23 are adapted to straddle the joint, as shown in Figures 1 and 4. In this position the clamp may be held frictionally or by other appropriate means. When lifted off, the tool may be removed by sliding the shank 14 laterally, as indicated in Figure 7 and another tool having its own shank may be substituted.

The frame shank 18 is carried by a post or standard 25. This post is erected on the forward end of one of the spaced parallel frame bars 26. The opposite frame bar is indicated at 27. These frame bars are connected together by the cross bars 28 and 29 which are perforated or otherwise formed to receive the screws 30 or other fastenings by which the base of the electric motor 31 is secured to the frame. The cross bars 28 and 29 are set inwardly from the ends of the longitudinal bars 26 and 27; and the post 25 is carried by the forward extension of one of the frame bars 26. This forward extension also carries an inwardly and laterally projecting stud 32 having a reduced threaded part 33, as shown in Figure 3. This stud is designed to receive the hub of the supporting wheel 34, which is preferably rubber tired. A nut 35 threaded on the part 33 suffices to hold the wheel in place.

The rear cross bar 28 is provided cen-

trally with a rearwardly extending bar 36 from which rises a standard 37 carrying the rearwardly projecting handle 38.

The pulley of the motor is shown at 39 5 and its belt at 40. This belt engages over the driven pulley 41, having at one side the eccentric pin 42 for the connection to the link 43, said link being also pivotally coupled to the tail piece 44 of the movable 10 scissors blade 12.

The pulley 41 is mounted on a shaft 45, one end of which is fixed in the vertical portion 46 of an angle bracket having a horizontal portion 47 extending parallel with 15 and beneath the shaft 45. This horizontal portion 47 is formed with the down-turned edge 48 which extends against the tool shank 14 to which it may be secured by screws or other appropriate fastenings. A supporting bearing block 49 for the outer end of 20 the shaft 45 is supported upon the shank 14 and between this bearing block 49 and the vertical part 46 of the bracket is disposed a coil spring 50 which surrounds the 25 shaft 45 and takes up the end thrust or play. A washer 51 may be interposed between the bearing block 49 and the pulley 41.

A washer 52 and nut 53 are shown as 30 used to hold the pulley 41 on the shaft 45. The electric current wires to the motor are shown at 54. These wires extend up through an opening 55, shown in Figure 3, as being made in an extension plate 56 of the frame opposite to this stud 32. In this 35 extension plate 56 and along side the opening 55 is a second opening 57 to receive and support the lower end of the bracket standard 58, shown in Figures 4 and 5.

The upper end of this standard at one 40 side carries a clamp ring 59 for receiving a plug or wire coupling. The bracket standard 58, which is preferably made from wire, is bent away from the ring 59 into an arm 60 having an upturned end 61 terminating 45 in one or more convolutions 62 forming a ring through which the wires, indicated at 63 from the plug pass to the source of electricity.

In Figures 8 to 10 there is shown several 50 other implements which may replace the shears. For instance in Figure 8 there is shown a grinding or polishing wheel 64 having associated therewith a pulley 65 which is adapted to be engaged by the belt 40. The pulley 65 and grinding wheel 64 are 55 carried by the shank 14^a, which shank is constructed as a complement to the shank 18 of the machine frame.

In Figure 9 a brush 66 is shown associated 60 with a pulley 67 for driving the same through the belt 40. In this instance the shank 14^b carries the brush and pulley and is constructed with the same form of joint shown in Figures 6 and 7.

In Figure 10 the shank 14^c is shown as

having the pulley 68 mounted on the shaft 69 which is adapted to receive the hollow sifting drum 70, the drum being provided with square openings 71 in its heads or ends to receive the square shaft 69 in order to 70 lock the drum to the shaft and cause the rotation of the drum when the pulley 68 is being driven. A nut 72 is adapted to be secured onto the threaded end 73 of the shaft in order to retain the drum in place. 75 The drum is provided with a perforated periphery 74 through which powder, seed or other material may be scattered.

In the use of the device, the machine is held in one hand by grasping the handle 38. 80 The machine is balanced on the single supporting wheel 34 which minimizes the friction and the effort spent to propel the machine. The wires from the house current or other source are so disposed in the supporting bracket that they can be kept clear of the machine during its movement. The machine is pushed with the shears or other implements, such as shown in Figures 8, 9 and 10, moving in advance. As the machine 85 progresses, the electric motor 31 will drive the shears or rotate the grinding wheel, brush or sifting device. A change can readily be made from one tool to the other by first lifting the clamp 21 and laterally shift 90 the shank 14 away from the companion shank 18. The belt can now be removed from the pulley and the new part substituted. The shank of the other tool is then substituted in its place, the clamp 21 replaced and 95 the belt 40 or another belt fitted to the electric motor and to the drive wheel of the pulley. The tension on the spring 50 may be regulated by rotating the nut 53 in one or the other direction. It is to be understood 100 that other forms of tools may be used than those illustrated. The circular stone 64, shown in Figure 8, may be used for removing rust from metal surfaces and the machine for this reason will be extremely useful to 105 automobile painters. The machine is inexpensive in that a single motor suffices for operating a great variety of tools and the expense of having a complete machine for each tool is avoided. 115

It is obvious that various changes and modifications may be made in the details of construction and design of the above specifically described embodiment of this invention without departing from the spirit thereof, such changes and modifications being restricted only by the scope of the following 120 claims.

What is claimed is:—

1. A portable electric tool driving machine 125 comprising a movable frame, a motor thereon, a shank on the frame having a beveled and cut away end portion with a non-circular perforation laterally therethrough, a tool driven by the motor and having a shank 130

with a cut away end portion having a beveled shoulder adjacent thereto and a non-circular lug for fitting in the opening in the frame shank portion, and a clamp for fitting 5 about said shanks at their juncture to prevent lateral separation thereof.

2. A portable electric tool driving machine comprising a movable frame, a motor thereon, a tool carried by the frame, a shaft, a 10 bracket on the tool fixedly carrying one end of the shaft, a coil spring about the shaft, a bearing block extending about the shaft and resting on the tool, and connections between the motor and said shaft for driving the tool.

15 3. A portable electric tool driving machine

comprising a movable frame, a motor thereon, a tool having a shank removably carried by said frame, an angle bracket carried by said shank and offset inwardly, a shaft having one end fixed to said bracket, a bearing 20 block supported on the shank and receiving the other end of said shaft, a coil spring wound about said shaft between the bracket and bearing block, a pulley mounted on said shaft outwardly of the bearing block, means 25 for retaining the pulley on the shaft and for adjusting the tension of said coil spring, and a belt connection between said motor and pulley.
